HIS ATTORNEY IN FACT

UNITED STATES PATENT OFFICE.

RAYMOND N. EHRHART, OF EDGEWOOD, PENNSYLVANIA, ASSIGNOR TO WESTINGHOUSE ELECTRIC & MANUFACTURING COMPANY, A CORPORATION OF PENNSYLVANIA.

CONDENSER.

Application filed February 8, 1915. Serial No. 6,835.

To all whom it may concern:

Be it known that I, RAYMOND N. EHRHART, a citizen of the United States, and a resident of Edgewood, in the county of Allegheny and State of Pennsylvania, have made a new and useful Invention in Condensers, of which the following is a specification.

This invention relates to condensing apparatus, and has for an object to produce such apparatus in which means are employed whereby the water of condensation discharged from the condenser may be utilized as the heating agent in a heating system.

A further object is to produce means for automatically controlling the delivery of condensing water to a jet condenser, operating in connection with a heating system in which the condensing water discharged from the condenser is employed as the heating agent.

A further object is to produce a jet condenser provided with new and improved means such that the condenser may be employed in connection with a heating system to which the water discharged from the condenser is delivered.

In condensers in which the condensing water is received at normal temperatures and is discharged at normal discharge temperatures, normal variations in the quantity of steam delivered to the condenser occasion relatively small variations in the pressure within the condenser and consequently do not materially affect the delivery of condensing water to the condenser. For example, condensers as ordinarily built are designed to maintain about a 28" vacuum, i. e., about one pound absolute pressure, with the injection water at 70° F. Average practice indicates that, under the above conditions, the best results are obtained by circulating a quantity of water through the condenser which will give a rise in temperature in the water of about 25° F., so that the

discharge water will have a temperature of about 95° F. The steam temperature corresponding to a 28" vacuum or one pound pressure, absolute, is 101° F. The statement, therefore, may be made that in ordinary practice condensers are so designed that the temperature of the discharge water is about 6° F. less than the temperature existing in the condenser. If such a condenser receives an amount of steam which exceeds the nor-

mal amount delivered to it by 50%, the temperature rise of the water will increase correspondingly; that is, the temperature of the discharge water will rise about 37½° F. or to 107°. The steam temperature within the condenser, under these conditions, would average about 114° F., which would correspond to about a 27" vacuum. Correspondingly, if the load were entirely taken off the condenser, practice shows that the vacuum would rise to about 29". In other words, a condenser designed for normal service at 28" vacuum would give a 27" vacuum or 1½ pounds absolute, receiving 50% excess steam, and a 29" vacuum, or ½ pound absolute pressure, while receiving practically no steam.

Now, it is evident that, if the atmospheric pressure is 15 pounds absolute, there will be little variation in the flow of water into the condenser due to variations in the amount of steam delivered to it. That is, if the higher pressure or atmospheric pressure is 15 pounds absolute and the pressure in the condenser varies only from ½ pound to 1½ pounds absolute, it will be apparent that the difference in the pressure which is effective in forcing the water into the condenser will not vary greatly under the normal operating conditions of the condenser. When the higher vacuum exists in the condenser, i. e., 29" or ½ pound absolute, the difference in pressure between atmospheric and internal pressure in the condenser is 14½ pounds, while when the lower vacuum exists in the condenser, that is, a 27" vacuum or 1½ pounds absolute, the difference in pressure is 13½ pounds. Now the flow of liquids is approximately proportional to the square root of the pressure difference occasioning the flow and it is therefore evident that the flow of water entering the condenser under varying pressure conditions within the condenser will vary between the square roots of 13½ and 14½, a difference of only a small percentage under widely varying operating conditions of the condenser. Under such conditions the pump discharging water from the condenser would have to be designed to handle only a small percentage of increase in order to discharge the excess water delivered to the condenser while a 29" vacuum was maintained.

Where a condenser delivers its discharge

water to a heating system and receives condensing water at a relatively high temperature, the conditions with respect to variation in the amount of water delivered to the 5 condenser under varying operating conditions are such as to render it practically impossible to design a discharge pump which is capable of handling the excess water delivered to the condenser during high vacuum 10 conditions, and of preventing flooding of the condenser and possible injury to the engine or apparatus served by it. In such an installation the pressure differences occurring in the condenser, due to variations in the 15 amount of steam delivered to it, are greater than in a condenser receiving water at ordinary or relatively low temperatures and operating under normal service conditions.

In the case of a condenser designed to 20 receive condensing water at 150° F. and to discharge at 175° F. while receiving a normal amount of steam to be condensed, a pressure of about 7½ pounds would be maintained within the condenser under normal 25 operating conditions. If the amount of steam delivered to the condenser is reduced so that practically none enters the condenser, an absolute pressure of about 4.2 would result in the condenser. If, however, 30 the steam delivered to the condenser is increased to such an amount that the temperature rise in the condensing water within the condenser is increased 50%, an absolute pressure of about 10 pounds absolute would 35 result within the condenser. With atmospheric pressure at 15 pounds absolute the difference in pressure between atmospheric and that within the condenser would vary, under the varying operating conditions, 40 from 5 to 11 pounds. Consequently, with the same resistance to flow in the injection line there would be a tremendous difference in the amount of water delivered to the condenser under high and low vacuum conditions. 45 It would be satisfactory to equip a condenser operating under such conditions with a discharge pump of sufficient capacity to discharge the maximum amount of water that could be drawn into the condenser, if 50 the pump only had to discharge into a pond or tank. Where water from the condenser is discharged into a heating system, an increase in the size of the pump, to take care of the maximum discharge demand, will not 55 be satisfactory, since the inertia of the water in the long and circuitous piping of the heating system will prevent the pump from discharging the water as rapidly as the variations in its flow into the condenser 60 occur, and consequently, some automatic means must be provided for controlling the delivery of water to the condenser under the varying conditions, else the condenser will flood during high vacuum conditions. 65 Suppose, for example, a condenser, de-

livering its discharge water to a heating system, were serving an engine, and, as is ordinarily the case, the load varied somewhat on the engine. From the foregoing it will be evident that if the load varies from no load to maximum load, there would be a great variation in the amount of water drawn into the condenser unless a regulating device is employed for controlling the delivery of water independently of the pressures existing within the condenser, and the discharge pump could not respond to the fluctuations in the amount of water drawn into the condenser because it could not increase the rate of flow of the discharge water 70 through the long piping system with sufficient rapidity to take care of the rapid fluctuations in the flow of water to the condenser. The result would be that if the load on the engine were suddenly decreased 75 to no load, there would be a rise within the condenser and an extra amount of water drawn into it. The tremendous inertia of the water in the heating system would prevent a rapid increase in the rate of discharge 80 flow and the condenser would fill up with water, flood, and possibly wreck the engine served by it.

One of the objects of the present invention is therefore to prevent flooding of the condenser under conditions such as described and to render it possible to employ a pump of moderate capacity, or one having just sufficient capacity to handle the water delivered to it under the ordinary operating 90 conditions of the condenser. This with the other objects above set forth is accomplished by means of apparatus having the features herein described and illustrated.

In the drawings accompanying and forming a part hereof, Figure 1 is a sectional view of condensing apparatus embodying my invention.

Figure 2 is a sectional view along the line 2—2 of Figure 1 and illustrates a float valve 105 which forms a detail of the present invention.

Fig. 3 is a diagrammatic view of the complete system.

Referring to the drawings: The condenser illustrated includes a condensing chamber 3, to which the steam to be condensed is delivered through a port 4. The condensing water is delivered to the condenser through a supply pipe or passage 5, which communicates with a series of jets 6, discharging downwardly through the condensing chamber 3. A converging deflector or mixing cone 7 is axially aligned with the series of jets 6 and is located between the inlet port 4 and the discharge port 8 of the condenser. A pump 9 of any desired type communicates with the discharge port 8 and, withdrawing the water from the condenser, delivers it through a pipe or passage 11 to a 120 125 130

heating system 11' in which the water is employed as the heating agent.

The pipe 5 communicates with any suitable source of supply, such for example as 5 an open cooling tank 5' which may be located above or below the condenser, as the operating conditions may require, and into which the return from the heating system discharges. In order to prevent flooding 10 of the condenser resulting from a falling off in the pressure within the condenser, I have provided a valve 12 within the pipe or passage 5 for controlling the flow of water passing therethrough. As illustrated, 15 the valve is of the butterfly or damper type and is actuated by means of a float 13 located within a chamber 14, in open communication with the chamber 3 of the condenser and so arranged that the water will 20 stand at the same level in it as in the condenser. The float is adapted to open the valve 12 as the water level in the condenser falls, and to close it as the water rises in the condenser. With such an arrangement, 25 the delivery of water to the condenser is controlled by the water level within the condenser and consequently flooding of the condenser is impossible while the pump 9 is in operation.

30 The valve 12 and its actuating float 13 are of simple construction and by providing the chamber 14 around the pipe or passage 5, it is unnecessary to provide glands for the valve trunnions 15 and, consequently, the valve will operate freely in response to varying positions of the float.

The operation of the apparatus is as follows: Under normal operating conditions the water level within the condenser is maintained at a determined height and consequently the valve 12 occupies such a position that it will maintain the desired conditions within the condenser by proportioning the flow of water to the condenser 45 to meet the existing conditions. If now, the steam delivered to the condenser falls off below that which is delivered under normal operating conditions, the pressure within the condenser will be diminished.

50 the flow of water through the passage 5 will be accelerated due to increase in the difference between the external pressure and that existing in the condenser and, as a result, the water level in the condenser will rise. This, 55 however, will cause the valve 12 to close more or less and will retard the flow of water to the condenser. If the water level in the condenser still continues to rise, the valve 12 will continue to close until it has finally 60 reached such a position that the flow of water to the condenser is so diminished that the normal condenser pressure will again be obtained, due to the fact that the condensing water will be heated to the normal 65 discharge pressure in condensing the limited

amount of steam delivered to the condenser. As the pump 9 withdraws the water from the condenser, the water level in the condenser will again fall and the valve 12 will open and finally assume a position of 70 equilibrium such that the amount of water delivered by it will equal the amount of water discharged by the pump 9. In this position the valve delivers water somewhat in excess of that required to maintain the 75 normal condenser pressure and consequently as the load conditions on the engine, served by the condenser, return to normal and a normal amount of steam is delivered to the condenser, the pressure in the condenser will rise and thereby decrease the effective head of the water entering the condenser through the passage 5. This will reduce the velocity of the flow of the water and consequently the amount delivered to the condenser, and the pump 9 will discharge water from the condenser faster than it is delivered by the valve 12 at the setting described. Consequently, the water level in the condenser will fall to normal and the valve will 85 again assume its normal position. If, now, the steam delivered to the condenser exceeds that which is delivered under normal operating conditions, the pressure in the condenser will rise above the normal pressure 95 and the flow of water through the pipe 5 will be retarded so that, with the existing valve setting, the pump 9 will be capable of lowering the water level in the condenser. As the water level falls, the valve 12 will 100 open an additional amount and consequently will deliver more water to the condenser until a position of equilibrium is attained corresponding to the amount of steam delivered to the condenser.

105 While I have illustrated and described one embodiment of my invention, it will be apparent to those skilled in the art that various changes, substitutions, modifications, additions and omissions may be made in the 110 apparatus illustrated without departing from the spirit and scope of my invention, as set forth by the appended claims.

What I claim is:

1. In combination with a jet condenser, 115 a hot well having a lateral extension, a conduit for delivering cooling water to the condenser and passing through said lateral extension, a valve in said conduit within the extension, and a float responsive to variations in level of the water in the hot well for controlling said valve, said float being connected to the valve wholly within the lateral extension of the hot well so that leakage around the connection will pass directly into the hot well.

120 2. In a jet condenser, a hot well, a conduit for delivering cooling water to the condenser passing through at least a part of the hot well, a valve in said conduit at a 130

- point within the hot well, and a float within the hot well for controlling said valve and the amount of water delivered to the condenser.
5. 3. In a jet condenser, a hot well, a conduit for delivering cooling water to the condenser, a valve in said conduit for controlling said delivery, a chamber surrounding said conduit and said valve, said chamber 50 being in open communication with the hot well, a float for controlling said valve located within said chamber and responsive to variations in level in the water therein, and loose fitting connecting means between said 55 float and said valve for preventing sticking or jamming of the float and valve, leakage around said means being conducted to the hot well.
6. The combination with a jet condenser 60 receiving a variable amount of fluid to be condensed and consequently subjected to fluctuating vacuum pressures and having a condensing water supply subject to such fluctuating pressures and responsive thereto, of 65 a water circulating heating system in which the inertia of the water flowing therethrough is materially greater than the inertia of the condensing water flowing to the condenser, means for withdrawing condensate and condensing water from the condenser and delivering them to the water circulating system, and means for automatically controlling the condensing water supply so as to prevent the combined amount of condensate and condensing water entering the condenser from exceeding the amount of water being delivered to the heating 70 system.
7. In combination, a jet condenser adapted to receive a variable amount of fluid to be condensed and consequently subjected to fluctuating vacuum pressures, a condensing water supply subject to such fluctuating pressures and responsive thereto, a water circulating heating system in which the flow of water therethrough is less responsive to fluctuations in pressure within the condenser than the flow of condensing water to the condenser, means for withdrawing water from the condenser and delivering it to the circulating system, and means for automatically controlling the condensing water supply so as to prevent the combined amount of condensate and condensing water entering the condenser from exceeding the amount of water passing through the circulating 75 system.
8. In combination, a jet condenser adapted to receive a variable amount of fluid to be condensed and consequently subjected to fluctuating vacuum pressures, a condensing water supply subject to such fluctuating pressures and responsive thereto, a water circulating heating system, including a pump, communicating with the condenser, receiving condensate and condensing water therefrom and adapted to circulate the water through the system the flow through which 80
- is less responsive to fluctuation in pressure within the condenser than the flow of the condensing water supplied, and means for automatically controlling the condensing water supplied so as to prevent the combined amount of condensate and condensing water 85 entering the condenser from exceeding the amount of water passing through the circulating system.
9. In combination, a jet condenser, a condensing water supply pipe and a steam supply pipe for the jet condenser, a pump communicating with the discharge port of the condenser, a water circulating heating system receiving the condensate and the condensing water from the pump, an open reservoir receiving the discharge from the heating system and delivering water to the condensing water supply pipe, a means, including a valve in the condensing water pipe, for automatically controlling the condensing water supply so as to prevent the combined amount of condensate and condensing water entering the condenser from exceeding the amount of water being delivered to the heating system.
10. In combination, a jet condenser adapted to receive a variable amount of fluid to be condensed and consequently subjected to fluctuating vacuum pressures, a condensing water supply subject to such fluctuating pressures and responsive thereto, a water circulating heating system in which the flow of water therethrough is less responsive to fluctuations in pressure within the condenser than the flow of condensing water to the condenser, means for withdrawing water from the condenser and delivering it to the circulating system, and means for automatically controlling the condensing water supply so as to prevent the combined amount of condensate and condensing water entering the condenser from exceeding the amount of water passing through the circulating system.
11. In testimony whereof, I have hereunto subscribed my name this 5th day of February, 1915.
- RAYMOND N. EHRHART.
